UNITED STATES PATENT OFFICE.

EUGENE A. FORD, OF UXBRIDGE, MASSACHUSETTS.

BALANCED INTERNAL-COMBUSTION MOTOR.

1,149,433.

Specification of Letters Patent. Patented Aug. 10, 1915.

Application filed November 15, 1911. Serial No. 660,475.

To all whom it may concern:

Be it known that I, EUGENE A. FORD, of Uxbridge, in the county of Worcester and State of Massachusetts, have invented certain new and useful Improvements in Balanced Internal-Combustion Motors, of which the following is a specification.

The present invention relates to motors or engines of which the motive power is furnished by the combustion of fuel in the working chambers or cylinders of the engine.

More particularly the invention relates to that class of internal combustion motors in which the fuel is injected into a volume of air already compressed in the combustion chamber and is there burned, instead of being mixed with air before compression, although in some of its aspects the invention is not limited to this particular type or class of internal combustion motors.

The objects of the invention are principally the following:—First, to provide a motor which is perfectly balanced, not only mechanically as regards the reciprocating parts, but also as to the forces other than inertia acting upon these parts; second, to provide a means by which only the resultant representing the excess of power delivered in the working stroke over that absorbed in the compression stroke, is delivered to the shaft, or, in other words, to provide for relieving the shaft of the necessity of transmitting and applying power for the compression stroke; third, to provide for relieving the engine frame or casting of end thrust reactions, and thereby eliminating vibration; fourth, to provide an engine in which the shaft is perpendicular to the cylinders, with means for applying equal powers on each semi-revolution in opposite directions at the same time; fifth, to provide a motor having two pistons moving toward and from one another in the same working chamber, with means for confining the combustion of the fuel to the central part of the chamber.

The foregoing and other objects are secured in an engine constructed as illustrated in the accompanying drawings, and described in the following specification, which engine is here shown to illustrate one of the many possible forms or designs of engine in which the ideas constituting this invention may be embodied.

In the accompanying drawings, Figure 1 represents a side elevation of the engine referred to. Fig. 2 is a vertical section. Fig. 3 is a plan view of the engine. Fig. 4 represents a cross section on line 4—4 of Fig. 2. Fig. 5 represents a cross-section on line 5—5 of Fig. 2. Fig. 6 is a detailed sectional view somewhat diagrammatic in character of the fuel injecting means by which the speed of the motor is controlled.

The same reference characters indicate the same parts in all the figures.

The preferred engine unit consists of four pistons working either in two cylinders arranged side by side, or in a single cylinder. In the present case the two cylinder unit is illustrated. Here 10 and 11 represent the two cylinders, in the first of which are contained the pistons 12, 13, and in the second the pistons 14, 15. The pistons in each cylinder are designed to move simultaneously and oppositely, alternately approaching and receding from one another. Relatively opposite pistons in the respective cylinders are connected together, and also connected with the engine shaft so as to act in proper phase. One of the connections is shown in Fig. 2, being the one which connects the piston 12 in cylinder 10 with piston 15 in cylinder 11. This connection is conveniently a rod 16, which has secured to one end an arm 17, also secured to the piston 12 by a bolt 18, and at the other end a similar arm 19 secured to the piston 15 by a bolt 20. The rod 16 carries a wrist pin 21 which is joined to a crank 22 on the engine shaft 23 by a connecting rod or pitman 24, shown in elevation in Fig. 1. An exactly similar rod 25 is connected to the piston 14 by an arm 26, to the piston 13 by an arm 27, and to a crank 28 on the engine shaft by a connecting rod 29 and wrist pin 30. The cranks 22 and 28 extend oppositely from the shaft and are placed as near together as the construction of the engine will permit. In the illustrations here given the distance between the cranks is slightly greater than the diameter of the cylinder, but it may be made less. The rods 16 and 25 travel longitudinally through guides 32 between the cylinders, and the arms 17, 19, 26 and 27 pass through openings in the sides of the respective cylinders.

It is within my contemplation to modify the mechanical construction and arrange-

ment of the means for connecting the several pistons together and to the shaft, in many ways, and accordingly I do not limit my invention to the particular arrangement shown.

- 5 It will be understood that as a result of the connections described, pistons 12 and 15 travel in unison and pistons 13 and 14 also travel in unison, but oppositely to the other 10 two pistons. Also that there are two moving pistons in each cylinder, or in other words that both end walls of each cylinder move together and apart in the compression and working strokes respectively. Thus, 15 whenever the pistons in either cylinder separate in the expansion or working stroke, the pistons in the other cylinder are forced toward one another in the compression stroke.
- 20 The engine here illustrated is designed to work on the two-stroke cycle, and in my description, whenever it is necessary to refer to the cycle I will assume that it is a two-stroke cycle. In this, however, I do not 25 wish to be understood as excluding the four-stroke cycle, or as limiting my invention wholly to a two-cycle engine, for the main principles of the invention are applicable to four-cycle engines as well. As, however, 30 I consider that the two-cycle engine is preferable for many reasons to the four-cycle engine, I have chosen to employ the two-cycle type in working out the invention. I have provided air inlets in the ends of the 35 cylinders for admitting fresh charges of air. These are controlled by valves 33 illustrated conventionally in Fig. 2, arranged to open inwardly and controlled by springs 34. Thus suction spaces are provided at 40 the ends of each cylinder, which spaces are kept distinct from the combustion chambers by means of the pistons and the cylinder walls, and the suction chambers of the two cylinders are also made strictly 45 separate. A conduit 35 connects the two suction spaces of the cylinder 10, and a similar conduit 36 in like manner connects the suction chambers of the cylinder 11. These conduits are connected with their respective 50 cylinders by short connecting passages 37 and 38, from which ports 39 and 40 open into the combustion chambers, such ports being uncovered by the pistons when at the end of their working stroke. Exhaust ports 55 41 and 42 for the two cylinders are at the respectively opposite ends of the combustion chambers, and are controlled by the pistons 12 and 14 respectively. They open into conduits 43 and 44, which are of greater width 60 than and surround the conduits 35 and 36 respectively. Outlets for the exhaust conduits are shown at 45 and 46, whence the exhaust excess may pass to the atmosphere or to a suitable muffler. The transfer conduits and exhaust conduits may, of course 65

be arranged in any convenient manner other than that shown, if desired, without departing from the spirit of the invention.

It will be noted that by making both end walls of the combustion chamber movable, 7 it is possible to locate the inlet and exhaust ports at opposite ends of the combustion chamber, and thereby secure a better scavenging effect than is possible in the usual construction of two-cycle engine, where the 7 inlet and exhaust ports cannot be farther separated than the amount of the diameter of the cylinder, and in which there is a considerable space toward the head end of the cylinder which is only imperfectly cleared 30 of exhaust gases.

In the engine illustrated, which is of the Diesel type, only air is drawn past the inlet valves 33. The fuel is separately injected through inlets 47, located in the sides of 85 the cylinders at the longitudinal centers thereof, so that the injected fuel may pass into the cylinders between the pistons when the latter are nearest together. In order to produce an agitation of the air, insuring 90 thorough combustion of the fuel and distribution of heat, and also to confine the zone of most intense combustion to the axis of the cylinder and away from the cylinder walls I mount upon each piston a wall or 95 plate 48 separated from the end of the piston by a space 49 and from the cylinder walls by an annular space 50 around its edges. Posts 51 or equivalent means support the plate 48 in proper relation to the 100 piston. These plates are so located that they approach closely together at the end of the compression stroke, but are separated sufficiently to permit the jet of fuel forced in through the inlet to enter between them. 105 Of course at the moment of injection the spaces between and surrounding the plates are full of air at great pressure and high temperature, the temperature being usually high enough to ignite the fuel. As soon as the pistons move apart, the air rushes from the spaces 49 around the edges of the plates 48 on all sides thereof. The air thus passing on the side nearest the inlet draws the fuel, which is injected in a finely divided condition, toward the center of the cylinder, where it meets the air passing around other points of the plates. These currents of air thus meeting produce agitation, causing sufficient fresh air to mingle 115 with the fuel for the purpose of completing the combustion thereof. As long as the separating movement of the pistons continues, and as the pressure in the combustion chamber diminishes, the air continues to 120 flow from the spaces 49 around the plates next to the cylinder walls, keeping the zone of combustion away from the walls and preventing deposit on the latter of sooty and tar constituents of the fuel. I prefer to 125

secure ignition of the fuel by compressing the air to such a degree that the temperature thereof is above the degree at which combustion commences, but I do not by any means limit the invention to an engine constituted to secure this effect, as I intend in some instances to limit the compression to a lower degree and provide an igniter of some sort. It is also within the contemplation of my invention to design the engine to run with a mixture of air and vaporized fuel made before admission to the cylinder, and in such case a carburetor will be connected to the fresh air inlets so as to supply a mixture of air and the vaporized fuel instead of fresh air alone. The stroke is designed for each engine to secure the desired effect, whether this is to obtain a temperature high enough for ignition, or to compress an explosive mixture to a degree less than that at which ignition occurs.

The engine constructed substantially as described has many important advantages. In the first place the moving parts are connected together in such a way that two equal masses are formed which move exactly oppositely to one another with the same accelerations, and thus the engine is mechanically balanced. In the second place the thrust and reaction caused in either cylinder by combustion of a charge are taken up by oppositely moving pistons and both applied to the shaft. Thus neither is endwise pressure applied to the engine frame, nor is any unbalanced pressure applied to the shaft. The only stresses absorbed in the engine frame are those normal to the cylinder walls, which, of course, are balanced. There is no tendency to vibration, therefore, and it is not necessary to provide strong or massive bed plates or foundations for the engine, even when the same is designed to develop great power. Finally the power necessary to give the pistons their compression stroke is furnished directly by the connected pistons making the working stroke, and is not transmitted first from the working piston to the shaft and thence to the compressing piston. Instead, so much of the power of the working piston as is required to actuate the compressing piston is taken by the rods 16 and 25, and only the difference between the pressure of the working stroke and the resistance of the compression is delivered to the shaft. Thus the shaft is required only to carry the effective power of the engine and is not required to assist in the internal transfers of force within the engine itself. Thereby the shaft may be made lighter than for engines of the ordinary type developing the same power.

It will be seen that the engine is compact, that it may be light in construction, that it is not necessary to use excessive pains in securing it in place, and that there is very

little side thrust and therefore little friction in the main bearing.

The engine as above described represents the preferred unit for engines working on the two-stroke cycle, but the improvements constituting the invention may be applied in other units and to engines of different cycle.

It is possible to control the speed of the engine and keep it somewhere nearly constant by an automatic inlet valve such as is shown in Fig. 6. In this figure there is diagrammatically indicated a fuel reservoir at 55, a fuel pump at 56 and a cam at 57, the latter being on a shaft 58 which is driven by the engine shaft 23, or may be the engine shaft itself. A conduit 59 runs from the pump to the chamber 60 of the inlet valve, and a branch 61 opens into this conduit from the fuel reservoir. An outwardly opening check valve 62 is located at the inlet of the branch 61. The fuel inlet 47 opens from the valve chamber into the cylinder and is controlled by a valve 63. The latter is formed as a part of, or connected to, a piston 64 which fits in the chamber 60 and is pressed toward the cylinder by a spring 65. A passage 66 is formed through the valve and piston, making free communication between the combustion chamber and the space back of the piston 64, whereby the gas pressure on the latter is balanced. In each rotation of the cam 57 the pump plunger is drawn back and pushed forward, drawing a charge of fuel from the reservoir and forcing it into the chamber 60. In entering the latter chamber the fuel acts on the piston 64, moving it against the pressure of spring 65 and opening the valve 63. When the pump plunger again withdraws, due to the cam offset 67 having passed the roll 68, the fuel flows back out of the chamber 60 and the valve 63 closes under the influence of the spring 65. The valve is so formed that even when fully opened the inlet is still very restricted, so restricted that the full charge of the pump is not able to pass through it in the time required by the offset 67 to pass the roll 68 even when the engine runs at the slowest possible speed. Consequently, as the fuel supplied by the pump is greater in volume than can be passed through the inlet, the amount injected into the cylinder varies with the speed of the engine, being greater when the speed is low, and less when high. In this way an automatic check is given to development of excessive speed, and the engine is caused to speed up when running too slowly. The check valve 62 allows the amount which enters the cylinder in each pump stroke to be made up.

An adjustable abutment 67^a is provided for the spring 65. The latter is carried by a stem 68 threaded through a cap 69 on the valve chamber, and having an arm 70 for regulation. This arm may be operated

either by hand or by any sort of engine governor to adjust the tension of the spring 65 and thereby cause more or less fuel to enter the cylinder during a unit of time. 5 When the abutment is permanently adjusted the inlet valve is set for generally higher or lower speed, and when controlled by a governor the speed may be kept constant.

I have described the machine element to 10 which rotation is imparted by the pistons as a shaft. In using this term, however, I do not wish to be understood as limiting my invention to a combination in which the shaft is a cylindrical rod or bar rotating 15 about its own axis. It is within my contemplation to employ other mechanical elements as equivalents for a shaft, among which may be named a sleeve and a cam, and accordingly I intend the term "shaft" as used in 20 certain of the following claims to be understood generically and interpreted as including any rotating or revolving element capable of being given rotary movement by reciprocating parts through any connecting 25 driving means whatever.

I claim,—

1. In an internal combustion engine, the combination of an engine cylinder, a pair of pistons therein movable oppositely and simultaneously therein, inwardly opening air inlet valves located in the ends of said cylinder, an air transfer passage from the ends of said cylinder to the combustion space thereof, a fuel inlet supply between the pistons, and partitions carried by the pistons forming with the pistons storage spaces for the compressed air charge to be delivered in annular streams into the combustion space between the pistons on the working stroke and thereby confine the zone of most intense combustion to the center of the cylinder. 30

2. In an internal combustion engine, the combination of an engine cylinder having an air inlet at one end and an exhaust outlet at the opposite end, a pair of pistons movable oppositely and simultaneously in said cylinder and controlling said inlet and outlet, inwardly opening air inlet valves located in the ends of said cylinder, an air transfer passage from the ends of said cylinder to the combustion space thereof, a fuel inlet supply between the pistons, and parti-

tions carried by the pistons forming with the pistons storage spaces for the compressed air charge to be delivered in annular streams into the combustion space between the pistons on the working stroke and thereby confine the zone of most intense combustion to the center of the cylinder. 55

3. An internal combustion motor including a combustion chamber, movable members forming the opposite end walls of such combustion chamber and adapted to move toward and from one another, means for admitting fuel and air to the chamber between such end walls, said moving end walls having storage chambers for reception of the compressed air charge and means adapted to deliver the said charge in annular streams into the combustion space between the pistons on the working stroke and thereby confine the zone of intense combustion to the center of the engine cylinder. 60

4. In an internal combustion motor, a combustion chamber in which air is compressed, means for injecting fuel into the chamber, a circular imperforate partition of less diameter than said chamber supported by one end of said chamber and forming a storage space for the compressed air charge to be delivered in an annular stream into the combustion space on the working stroke and thereby confine the zone of intense combustion to the center of the combustion chamber. 75

5. In an internal combustion motor, a combustion chamber in which air is compressed, means for injecting fuel into the chamber, a piston working in said chamber and having an imperforate plate fast thereto and separated from the face of the piston and from the sides of the chamber and forming with the piston a storage space for the compressed air charge to be delivered in an annular stream into the combustion space on the working stroke and thereby confine the zone of intense combustion to the center of the combustion chamber. 80

In testimony whereof I have affixed my signature, in presence of two witnesses.

EUGENE A. FORD.
